(57) **CLAIM**

The ornamental design for a portable vehicle charger, as shown and described.

DESCRIPTION

FIG. 1 is a perspective view of a portable vehicle charger. FIG. 2 is a front elevation view of the portable vehicle charger of FIG. 1.

FIG. 3 is a right side elevation view of the portable vehicle charger of FIG. 1

FIG. 4 is a rear elevation view of the portable vehicle charger of FIG. 1.

FIG. 5 is a left side elevation view of the portable vehicle charger of FIG. 1.

FIG. 6 is a top plan view of the portable vehicle charger of FIG. 1; and,

FIG. 7 is a bottom plan view of the portable vehicle charger of FIG. 1.

The broken lines in the drawings are for the purpose of illustrating portions of the article and environmental subject matter that form no part of the claimed design.

1 Claim, 3 Drawing Sheets
